Primary Examiner — Darlington Ly

(57) **CLAIM**

The ornamental design for an electric bicycle, as shown and described.

DESCRIPTION

FIG. 1 is a top, front, right side perspective view of an electric bicycle embodying our new design;
FIG. 2 is a top, rear, left side perspective view thereof;
FIG. 3 is an enlarged front elevation view thereof;
FIG. 4 is an enlarged rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.
The broken lines shown in the drawings depict portions of the electric bicycle that form no part of the claimed design.

1 Claim, 8 Drawing Sheets
